UNITED STATES PATENT OFFICE.

JOHN MACKEY LARKIN, OF UNION, SOUTH CAROLINA.

CAR-COUPING.

SPECIFICATION forming part of Letters Patent No. 615,561, dated December 6, 1898.

Application filed February 9, 1898. Serial No. 669,677. (No model.)

To all whom it may concern:

Be it known that I, JOHN MACKEY LARKIN, of Union, in the county of Union and State of South Carolina, have invented new and useful Improvements in Car-Couplings, of which the following is a full, clear, and exact description.

This invention relates to an improvement in car-couplings of the link-and-pin type, and has for its object to provide a car-coupling of that character with novel features of construction which are adapted to absorb shocks due to the impingement of two couplings when coupled and also to permit a free lateral movement of the coupling-link when two coupling draw-heads are connected therewith.

The invention consists in the novel construction and combination of parts, as is hereinafter described, and defined in the appended claims.

Reference is to be had to the accompanying drawings, forming a part of this specification, in which similar characters of reference indicate corresponding parts in all the views.

Figure 1 is a sectional plan view of two couplings having the improvement substantially on the line 1 1 in Fig. 2. Fig. 2 is a sectional side view of the same, essentially on the line 2 2 in Fig. 1. Fig. 3 is a sectional plan view showing a modified form of a feature of the invention as applied to two car-couplings. Fig. 4 is a sectional side view of two draw-heads in coupled condition, the coupling-link being similar to that shown in Fig. 1, the other features of the invention being slightly changed in design; and Fig. 5 is a transverse sectional view substantially on the line 5 5 in Fig. 3.

In carrying into effect the features of invention the draw-head 10 of the improved car-coupling may with advantage be formed as shown, having the front end furnished with a thickening-rib to afford strength thereto. A recess or chamber *a* extends from the front end of the draw-head rearwardly therein, and the walls of the draw-head as well as the chamber mentioned are rectangular in cross-section.

A rabbet is formed in the front ends of the four walls of the chamber *a*, said rabbet being rearwardly extended a sufficient distance to produce a proper enlargement of the cham-

ber for the reception of the buffer-block 11 or 11^a. The buffer-block may be in the form of a short cylinder of hard wood and be incased by a jacket *c* of metal or may be of tough hard wood devoid of the casing. When the buffer-block is in cylindric form, as represented at 11 in Figs. 1, 2, and 3, the side walls of the draw-head are concaved where rabbeted, so as to adapt them to receive and loosely contact with the cylindric wall of the buffer-block or with the jacket *c* thereon, as the case may be.

As the top and lower walls of the cylindric buffer-block 11 are flat and parallel, it is of course necessary to rabbet the upper and lower walls of the draw-head to conform with said end walls of the buffer-block 11, and thus permit the free insertion of the latter until it is properly seated in the forward enlargement of the draw-head chamber, as is clearly shown in the drawings.

In Fig. 4 the buffer-block 11^a is represented as spherical, and to accommodate this form of buffer-block the front end of the draw-head chamber is suitably concaved on the inner corners, thus providing a cup-like seat or rabbet of a depth which will permit a proper embedment of the spherical buffer-block therein. The buffer-block, either in cylindric or spherical form, is diametrically slotted, as at *d*, for the reception of the coupling-link 12 or 12^a.

The link is preferably shaped as shown at 12 in Figs. 1, 2, and 4, comprising two sections that are jointed together at their opposing ends at *e*, so as to permit a lateral flexure of the same.

A longitudinally-disposed slot *f* is formed in the link 12 near the outer end of each section thereof, said slots being provided for the reception of two coupling-pins 13, as will be further explained.

The diametrical slots *d* in the buffer-blocks 11 or 11^a loosely receive the jointed link 12, and the ends of the latter project far enough from each side of the buffer-block to allow the projecting portions of the link to occupy the recess or chamber *a* in two draw-heads of the improved construction when they are to be coupled together.

The draw-head body is perforated vertically for the free insertion of a coupling-pin 13, which may be and preferably is in the form

of a cylindrical bar having an eye *g* at its upper end. The coupling-pin *13* when inserted may pass through the slot *f* in one section of the coupling-link *12*, that has been inserted within the chamber *a* of the draw-head, and thus loosely secure the link in the draw-head.

It is to be understood that when the link *12*, having the buffer-block *11* or *11^a* thereon, is secured at one end within the chamber *a* of the draw-head *10* the buffer-block will be maintained in engagement with said parts and the outer section of the link will be supported, so as to freely enter a like draw-head for coupled engagement therewith. Any approved means may be employed for lifting and dropping the coupling-pins *13*—such, for example, as a chain connection to the ordinary rock-shaft and arm thereon on a car—which in the usual manner will permit a manipulation of the coupling-pin from the side of the car in a safe manner, it being evident that other means may also be provided for such a purpose, and as this is not a feature of the improvement it is not deemed necessary to show the same in the drawings.

It will be seen that when two cars provided with the improved couplings are coupled together the wooden buffer-block that is interposed between opposite ends of the draw-heads will cushion the shocks sustained by the car-couplings while in service, and thus obviate injury to the cars and couplings.

From the peculiar construction of the link and buffer-block freedom is afforded for the lateral movement of engaged parts of two couplings when running on curves of a railroad, thus avoiding any cramping action, while end bumping of the couplings is prevented in a large degree.

The link may also be formed as shown in Figs. 3 and 5 at *12^a*. In this construction the slots *f* are dispensed with, and the two link-sections are widened at their outer ends to produce coupling-heads thereon. If the link is formed as shown in Figs. 3 and 5, a forked coupling-pin *13^a* is employed for securing the link within the draw-head chamber, and to permit such a furcated pin to be introduced

two vertical perforations must be formed in 50 the draw-head body, as shown at *h* in Fig. 5.

It will be seen that when the parallel members of the coupling-pin *13^a* are inserted within the draw-head *10* at the front of a head on the link *12^a* said link will be loosely secured 55 within the draw-head.

In case the cylindric buffer-block *11* is jacketed with a metal casing *c* the casing may have ribs *c'* at the ends, which will add to its durability and permit the casing to be made 60 of light plate metal.

Having thus described my invention, I claim as new and desire to secure by Letters Patent—

1. The combination with a chambered draw-head, and a jointed coupling-link securable therein, of a buffer-block at the front end of the draw-head and having a laterally-widened transverse slot through which the link passes, and within which it is adapted to flex laterally, 65 substantially as described.

2. The combination with a chambered draw-head, and a jointed coupling-link securable therein, of a buffer-block at the front end of the draw-head and having a laterally-widened 70 transverse slot through which the link passes, the joint thereof being located in said slot and thus adapted to flex laterally, substantially as described.

3. The combination with a chambered draw-head, and a coupling-link securable thereto, of a wooden buffer-block at the front end of the draw-head, and a metal jacket on said buffer-block, the block and jacket being slotted for the passage of the link therethrough, 80 substantially as described.

4. In a car-coupling of the character described, a transversely-slotted wooden buffer-block incased in a slotted metal jacket, and adapted to be held at the front end of the 90 draw-head by a coupling-link inserted through the slot thereof and secured in the draw-head, substantially as described.

JOHN MACKEY LARKIN.
